D11-101. OR D11,617 EX

UNITED STATES PATENT OFFICE.

HERMAN KNUBEL, JR., OF NEW YORK, N. Y.

DESIGN FOR A MEDALLION.

SPECIFICATION forming part of Design No. 11,617, dated January 27, 1880.
Application filed December 8, 1879. Term of patent 3½ years.

To all whom it may concern:

Be it known that I, HERMAN KNUBEL, Jr., of New York city, in the State of New York, have originated a Design for Medallions, of which the following is a full, clear, and exact description, reference being had to the accompanying photographic illustration, making part of this specification.

A represents the body of the medallion, and A' a rim or border thereof. B is a slightly-raised representation of the head of Gen. U. S. Grant in profile, with the face to the left. C is a corresponding representation of a portion of the bust in military costume.

I propose to make the medallion of such size

that the head and bust B and C shall be about half life size; but this may be varied.

What I claim as my invention is—

The design within described, consisting of the raised profile of Gen. Ulysses S. Grant, having military insignia C upon a background, A, and surrounded and inclosed by a raised border, A', the whole forming a rounded medallion, as described, and shown in the accompanying illustration.

H. KNUBEL, JR.
